CLAIM

The ornamental design for a container lid as shown and described.

DESCRIPTION

FIG. 1 is a top front prospective view of a container lid showing my new design;

FIG. 2 is a front elevation view of lid in FIG. 1;

FIG. 3 is a rear elevation view of the lid in FIG. 1;

FIG. 4 is a right-side elevation view of the lid of FIG. 1;

FIG. 5 is a left-side elevation view of the lid of FIG. 1;

FIG. 6 is a top plan view of the lid of FIG. 1; and,

FIG. 7 is a bottom plan view of the lid of FIG. 1.

In the drawings, the broken lines show portions of container lid that form no part of the claim.

1 Claim, 4 Drawing Sheets
